UNITED STATES PATENT OFFICE.

ELMER SMITH, OF FOND DU LAC, WISCONSIN.

TIMER-SUPPORTING BRACKET.

1,405,724.

Specification of Letters Patent. Patented Feb. 7, 1922.

Application filed December 14, 1921. Serial No. 522,196.

To all whom it may concern:

Be it known that I, ELMER SMITH, a citizen of the United States, residing at Fond du Lac, in the county of Fond du Lac 5 and State of Wisconsin, have invented certain new and useful Improvements in Timer-Supporting Brackets, of which the following is a specification.

The present invention relates to improvements in internal combustion engines, and has particular reference to a supporting element, for carrying a timer and distributor, for use in connection with the engine.

An important object of the invention is 15 to provide a device of the above mentioned character, which is adapted to be applied to a Ford automobile, upon the removal of the ordinary Ford commutator, without necessitating the use of additional bolts or 20 the like, or even unscrewing a single bolt of the engine.

A further object of the invention is to provide a device of the above mentioned 25 character, which is simple in construction, strong, formed of few and simple parts, and durable.

A further object of the invention is to provide a device of the above mentioned 30 character, having a casing engaging the flange of the crank case, which holds the ordinary Ford timer, and an ear or extension having an opening to fit over and receive the head of the bolt which supports the fan bracket.

Other objects and advantages of the 35 invention will be apparent during the course of the following description.

The present application is a continuation 40 in part of my copending application for combined timer and distributor, filed November 5, 1921, Serial No. 513,124.

In the accompanying drawings, forming 45 a part of this specification, and in which like numerals are employed to designate like parts throughout the same,

Fig. 1 is a perspective view of a device embodying my invention, showing the same in place upon a Ford automobile,

Fig. 2 is a side elevation of the device, 50 viewed from the inner side, parts being shown in central longitudinal section.

Fig. 3 is a detail horizontal section taken on line 3-3 of Fig. 1, and,

Fig. 4 is a fragmentary longitudinal section taken on line 4-4 of Figure 1.

In the drawings, wherein for the purpose

of illustration is shown a preferred embodiment of my invention, the numeral 10 designates a crank case of a Ford engine. This crank case carries the usual crank shaft 11, driving a pulley 12, engaged by a belt 13. This belt extends upwardly and engages a fan pulley 14, rotatable upon a shaft 15. The shaft 15 is carried by a vertically swinging or adjustable bracket or 65 arm 16, supported by a bolt 17, Fig. 4, which passes through a sleeve 18, formed upon the lower end of the bracket. The bolt 17 serves to clamp the bracket 16 in the desired angular position. 70

My improved support for the combined timer and distributor embodies a lower casing 19, which is approximately cup-shaped, and is tapered, decreasing in diameter outwardly. This casing is of the general shape 75 of the Ford commutator casing, and has a circular flange 20, at its inner end, adapted for insertion within the flange 21, formed upon the crank case. While the drawings show the flange 20 as fitting within the 80 flange 21, I also contemplate having the flange 20 arranged outwardly of the flange 21, the idea being that the flanges interfit or interlock. The casing 19 is held in position by the usual leaf spring 22 of the 85 Ford engine, which spring is employed upon the Ford engine for holding the Ford commutator casing in place. Extending upwardly from the casing 19 and preferably integral therewith is a sleeve 23, provided 90 with a lateral extension or plate 24, having an opening 25 therein. It is preferred that the opening 25 be sufficiently large to receive the head of the fan bracket supporting bolt 17, so that the head of the bolt is 95 arranged bodily within the opening 25. The advantage of this construction is that the device may be placed upon the Ford automobile, by the removal of the ordinary commutator casing, and securely held in place 100 by means of the spring 22 and bolt 17, without the use of additional bolts, or disturbing a single bolt upon the engine. The spring 22 holds the casing 19 in locked engagement with the flange 21 of the crank 105 case, and the head of the bolt 17 engaging within the opening 25, prevents the sleeve 23 and associated elements from partaking of lateral movement. The leaf spring 22 and extension 24 are upon opposite sides of 11 the sleeve 23. The numeral 25' designates a pivoted casing, disposed at the top of the

sleeve 23, and carrying a depending sleeve 26, pivoted within the collar 27, at the top of the sleeve 23. The sleeve 26 has an annular groove 28, receiving the reduced end 5 of a screw 29. The sleeve 26 is therefore free to turn but is held against longitudinal displacement.

Extending longitudinally within the sleeve 23 is an operating shaft 30, journaled at its 10 upper end in the pivoted sleeve 26, and at its lower end through a stationary bearing 31, held in a collar 32. A thrust ring 33 may be rigidly secured to the shaft 30 and engages the top of the bearing 31, to prevent 15 downward displacement of the shaft 30.

The numeral 34 designates a beveled gear, operating within the casing 19, and rigidly secured to the lower end of the shaft 30, and engaging a beveled gear 35, rigidly 20 mounted upon the cam shaft 36 of the engine.

A grease cup 37 is carried by the collar 27 and is adapted to feed grease between the sleeve 26 and the collar 27, and also to feed 25 the grease through the ports 38, between the shaft 30 and the bore of the sleeve 26.

The pivoted casing 25' is provided with a crank arm 39, which is to be suitably connected to the spark lever of the automobile, 30 and the casing 25' is turned in either direction to advance or retard the spark, as may be desired.

The casing 25' is provided with a cap or cover 37', formed of insulating material, and 35 suitably secured thereto.

The combined timing and distributing mechanism is mounted in the casing 25' and its cap 37'. The construction of this mechanism is not claimed per se in this application, and need not be given in detail. The mechanism includes a timing device 38', operated by the upper end of the shaft 30, and a distributing device 39'. The timing device of course controls the operation of 40 the primary circuit, including the primary coil, while the distributor controls the operation of the secondary circuit, including the secondary coil. The secondary circuit is connected with the spark plugs of the engine, as is well known. The complete construction of the timing and distributing mechanism is shown in my copending application for combined timer and distributor, filed November 5, 1921, Serial No. 513,124. 45

50 The invention is not restricted however to the use of this particular type of combined timer and distributor, as any other form of

suitable timer and distributor may be employed.

It is to be understood, that the form of my invention herewith shown and described is to be taken as a preferred example of the same, and that various changes in the shape, size, and arrangement of parts may be resorted to without departing from the spirit 60 of my invention or the scope of the subjoined claims.

Having thus described my invention, I claim:

1. In a device of the character described, 70 the combination with the crank case of a Ford automobile having a flange at the end thereof near the fan bracket, of a casing having one end thereof adapted to interfit with the flange, an upstanding sleeve carried 75 by the casing and provided upon one side with a lateral extension having an opening, said extension being so located and the opening therein of such a size that such opening is adapted to bodily receive the head of the 80 fan bracket supporting bolt, a leaf spring connected with the crank case upon the other side of the sleeve and engaging said casing and forcing the casing toward the crank case, a second casing secured to the 85 upper end of the sleeve and adapted to receive circuit closing means, and driving means for the circuit closing means including gears in the first named casing and a shaft extending longitudinally through 90 said sleeve.

2. In a device of the character described, 95 the combination with the crank case of a Ford automobile having a flange at the end thereof near the fan bracket, of a casing having one end thereof adapted to interfit with the flange, an upstanding member carried by the casing and provided upon one side with the lateral extension, said lateral extension being so located that it is adapted 100 to engage with the fan bracket supporting bolt, a leaf spring connected with the crank case upon the other side of the upstanding member and engaging the casing and forcing the same toward the crank case, a second 105 casing secured to the upper portion of the upstanding member, and adapted to receive circuit closing means, and driving means for the circuit closing means including gears in the first named casing and a shaft extending longitudinally of the upstanding member. 110

In testimony whereof I affix my signature.
ELMER SMITH.
